UNITED STATES PATENT OFFICE.

MIREILLE UBELMANN, OF PARIS, FRANCE.

DESIGN FOR A BEAUTY-CREAM CASKET.

57,954.

Specification for Design.

Patented May 17, 1921.

Application filed July 9, 1920. Serial No. 395,170. Term of patent 14 years.

To all whom it may concern:

Be it known that I, MIREILLE UBELMANN, a citizen of the French Republic, residing at No. 37 Rue de Bellefond, Paris, France, have invented a new, original, and ornamental Design for a Beauty-Cream Casket, of which the following is a specification, reference being had to the accompanying drawing, forming part thereof.

The Figure 1 is a front elevation view;
The Fig. 2 is a side view;

The Fig. 3 is a rear elevation view.

I claim—

The ornamental design for a beauty-cream casket, as shown.

In witness whereof I have hereunto set my hand in the presence of a witness.

M. UBELMANN.
